SAND PUMP

James E. Brazell, Joinerville, Tex., assignor of forty-five per cent to Charles E. Lafferty and ten per cent to Gordon Edgar, both of Rusk County, Tex.

Application July 25, 1936, Serial No. 92,485

4 Claims. (Cl. 166—19)

This invention relates to a sand pump and has particular relation to a pump which is specially adapted for use in removing sand from the well wherein the pump is located.

5 An object of the invention is to provide a sand pump which may be lowered into a well and whereby the sand shale, mud, or water collecting in the reservoir, in the well, may be removed a load at a time.

10 It is another object of the invention to provide, in a sand pump, a novel type of pump plunger wherein spaced plunger sections are yieldingly mounted on a tubular mandrel.

15 It is a further object of the invention to provide a pump of the character described having a novel type of foot valve.

With the above and other objects in view, the invention has particular relation to certain novel features of construction, operation and arrangement of parts, an example of which is given in this 20 specification and illustrated in the accompanying drawing, wherein:

Figure 1 shows a vertical sectional view of the pump barrel, showing an elevational view of the plunger therein.

25 Figure 2 shows a vertical sectional view of the plunger.

Figure 3 shows an enlarged vertical sectional view of the foot valve, and

30 Figure 4 shows a cross sectional view thereof taken on the line 4—4 of Figure 3.

Referring now more particularly to the drawing wherein like numerals of reference designate similar parts in each of the figures, the numeral 35 1 designates the cylindrical pump barrel screwed onto the lower end of which there is the tubular valve casing 2 having one side formed with the downwardly projecting extension 3. At the lower end of the casing 2 said casing is restricted inwardly forming the annular seat 4. A disc 5 is pivotally mounted in the lower end of the casing 2 and the disc is of a diameter to fit closely within and to pass through the seat 4. Beneath the seat 4 there is a plug 6 threaded through the 40 wall of the casing arranged opposite the pivot 7 on which the disc is mounted. When the disc is in transverse position as shown in Figures 1 and 4 the plug 6 may be screwed inwardly forming a stop to maintain the disc in transverse position. 45 The disc will thus be permitted to open upwardly to admit the load, as hereinafter explained, and will be maintained in transverse position to trap said load when the pump is withdrawn from the well. When it is desired to dump the load at the 50 ground surface the plug 6 may be screwed out-

wardly to clear the disc 5 to permit said disc to swing downwardly into the position shown in Figure 3 to permit the load to be dumped.

Attached to the upper end of the barrel there is a head 8 having the upstanding tubular neck 9 through which the operating cable 10 may work. The neck has the external downwardly pitched annular teeth 11 over which a grapping tool of conventional construction may be engaged should it be necessary to do so to remove the pump from the well in case the pump should become stuck therein. Normally the pump is lowered into the well and removed therefrom by means of the operating cable 10 which extends to the ground surface. The well will usually contain a casing 12 which is set therein above the oil producing stratum and above the reservoir 13 in which the oil collects and which also, in certain characters of formation, collects the sand, which it is desired to remove.

20 In the barrel and attached to the lower end of the cable there is a novel type of plunger which will now be described.

This plunger has a tubular mandrel 14 on the lower end of which there is fastened, in any preferred manner, a stop 15. Slidably mounted on the mandrel and spaced apart are the plunger sections 16 preferably formed of metal although they may be formed of any suitable material. Four of these sections are shown in Figure 1 but 25 a greater or less number may be employed if desired. These sections, except the lower one, are mounted on suitable coil springs 17 which surround the mandrel, each spring resting on the plunger section, or stop, beneath. These plunger 30 sections fit closely around the mandrel and closely within the barrel 1. They are relatively short so that if a gritty or cutting substance should find its way between a section and the barrel it will readily pass out and free itself during the manipulation of the plunger, particularly by reason of the fact that each plunger section is yieldingly mounted and will have a tendency to move up and down so as to easily free the offending object.

25 A tubular nipple 18 is attached to the upper end of the mandrel. The upper end of this nipple is formed with an annular valve seat 19 which is controlled by the upwardly opening ball valve 20. This valve is confined within a tubular cage 21 which has a cross rod 22 to limit the upward movement of the valve 20. The cage 21 also has the side openings 23 to permit the free outflow of liquid and the solid objects therein which may pass upwardly through the mandrel 14 while the 30

pump is being lowered into the well or during the reciprocation of the plunger.

The upper end of the cage 21 has the reduced extension 24 shaped to fit snugly into the socket 25 in the lower end of the head 8 when the plunger is elevated into its upper position, preparatory to removing the pump from the well.

The barrel 1 has the side outlets 26 adjacent its upper end to permit the discharge of liquid 10 and solid particles from the barrel upon upward movement of the plunger.

The lower end of the operating cable 10 is fitted downwardly through the upper end of the cage 21 and is suitably secured in the socket member 27 whose upper end fits up into the socket 28 within said cage and said socket member 27 may be fastened in place by a set screw 29 which is threaded through the wall of the cage 21. In order to fit the socket member 27 in place 20 and to secure the cable thereto a side opening 30 is provided in the cage 21 for access to the work.

In operation the pump is assembled as shown in Figure 1 and is then lowered into the well as 25 also shown in said figure, with the lower end of the pump in the reservoir 13. While the pump is being lowered the plunger will be in its upper position as is obvious but when the pump lands on bottom, the plunger will move downwardly 30 to the lower end of the pump when the tension on the cable is released, the fluid beneath the plunger passing upwardly through the mandrel 14, past the valve 20 and out through the openings 23. Upon upward pull on the cable 10, the 35 plunger will be moved upwardly and a load of sand will be drawn in from the reservoir 13 into the barrel 1, the disc 5 lifting to permit the inlet of the load. As the plunger is elevated the springs 17 will yield and be placed under a certain amount of compression, thus acting as shock 40 absorbers and to that extent relieving the sudden tension on the cable 10 and when the plunger has reached the limit of its upward movement the springs will expand to their former position. 45 This movement of the plunger sections will assist in displacing gritty substances that may collect between said sections and the barrel 1.

Sometimes the formation collected in the reservoir 13 is of a heavy plastic nature which flows 50 very reluctantly into the lower end of the barrel and upon attempted upward movement of a plunger as now commonly used in sand pumps a vacuum is formed in the barrel beneath the plunger to such an extent that the attempted 55 further upward movement of the plunger will have a tendency to cause a relative downward movement of the barrel further into the formation, either resulting in the breakage of the cable 10 or the sticking of the pump in the well. Under 60 these conditions when a plunger of the type herein described is used, the cable may be alter-

nately placed under tension and released, thus causing a vertical reciprocatory movement of the sections 16, due to the action of the springs 17, thus imparting vibrations to the pump with the result that the lower end of the barrel may be 5 released from the formation. When a load is obtained and the pump is elevated the disc 5 will be moved to closed position thus entrapping the load and the pump may then be pulled on out of the well and the plug 6 released as hereinbefore 10 explained to permit dumping of load.

The drawing and description disclose what is now considered to be a preferred form of the invention, by way of illustration only, while the broad principle of the invention will be defined 15 by the appended claims.

What I claim is:—

1. In a pump, a plunger comprising a tubular mandrel, sealing members around the mandrel and spaced apart, yieldable means between the 20 sealing members, a valve cage attached to the upper end of the mandrel and having an outlet, a seat beneath the outlet, an upwardly opening valve controlling said seat and means on the cage for the attachment of a cable thereto. 25

2. A sand pump comprising a tubular barrel, a foot valve at its lower end, a plunger in the barrel including a mandrel, and spaced sealing members around and movable longitudinally on the mandrel and shaped to fit in the barrel, coil 30 springs around the mandrel between the sealing members, means on the mandrel for the connection of an operating cable thereto and stop means on the upper end of the barrel to limit the upward movement of the plunger relative to 35 the barrel.

3. A sand pump comprising a tubular barrel, a foot valve controlling the lower end of the barrel, a head on the upper end of the barrel, provided with a socket, a plunger in the barrel including a tubular mandrel and spaced sealing members on and movable longitudinally relative to the mandrel, yieldable members between said sealing members, a valve controlling the upward flow of liquid through the mandrel, a valve cage attached to the upper end of the mandrel and confining said valve, an operating cable working through said head, means for attaching the cable to said cage, the upper end of the cage being reduced to fit into said socket upon the movement of said plunger to its upper position in the barrel. 45

4. In a pump a plunger comprising a tubular mandrel, sealing members around the mandrel and spaced apart, coil springs between the sealing members, a valve cage on the mandrel having an outlet, a seat beneath the outlet, an upwardly opening valve controlling the seat and means for connecting an operating member to the plunger. 55
